LIFE PRESERVER

David W. Bales, Washington, Mo., assignor to Hawthorn
Company, a division of Knellwood Company, Chicago,
Ill., a corporation of Delaware

Filed May 28, 1965, Ser. No. 85,492

Term of patent 14 years

(Cl. D71—1)

FIG. 1 is a front perspective view of a life preserver, embodying my new design;

FIG. 2 is a front plan view thereof on an enlarged scale;

FIG. 3 is a longitudinal sectional view taken substantially along the lines 3—3 of FIG. 2;

FIG. 4 is a transverse sectional view taken substantially along the line 4—4 of FIG. 2;

FIG. 5 is a transverse sectional view taken substantially along the line 5—5 of FIG. 2;

FIG. 6 is a transverse sectional view taken substantially along the line 6—6 of FIG. 2, and

FIG. 7 is a transverse sectional view taken substantially along the line 7—7 of FIG. 2.

The back of the article is plain.

I claim:

The ornamental design for a life preserver, as shown and described.
